CLAIM

The ornamental design for a tub for bathing, as shown and described.

DESCRIPTION

FIG. 1 is a right, top, front perspective view of a tub for bathing embodying my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a cross-sectional view taken along line 6—6 of FIG. 2;

FIG. 7 is a cross-sectional view taken along line 7—7 of FIG. 2;

FIG. 8 is a cross-sectional view taken along line 8—8 of FIG. 2;

FIG. 9 is a cross-sectional view taken along line 9—9 of FIG. 2; and,

FIG. 10 is a top plan view of a second embodiment which is a mirror image of that shown in FIG. 2, the front elevational view being a mirror image of that shown in FIG. 3, the left side elevational view being a mirror image of that shown in FIG. 4, and the right side elevational view being a mirror image of that shown in FIG. 5.

The broken line representations of holes in FIGS. 1-5 and 7-10 are for purposes of illustration only, and form no part of the claimed design.
